United States Patent Office.

ADAM WEAVER, OF PHILADELPHIA, PENNSYLVANIA.

Letters Patent No. 92,677, dated July 13, 1869.

IMPROVEMENT IN APPARATUS FOR MAKING MOULDS FOR METAL CASTINGS.

The Schedule referred to in these Letters Patent and making part of the same.

To all whom it may concern:

Be it known that I, ADAM WEAVER, of the city of Philadelphia, in the State of Pennsylvania, have invented a new and useful Improvement in, and Apparatus for Moulding Patterns in Sand for Castings; and I do hereby declare that the following is a full, clear, and exact description of the same, reference being had to the accompanying drawings, making a part of this specification, in which a circular arrangement of a series of four like moulding-devices is shown,

Figure 1 being a representation of the upper side of the moulding-table, or platform of the series;

Figure 2, a like representation of the parts below the said platform, or below the dotted horizontal line $x-y$ of fig. 3, a part of one of the moulding-series being removed therefrom;

Figure 3, a front elevation of one of the moulding-series, with a section of a pattern as being moulded in a detachable half-flask applied to the platform;

Figure 4, a vertical-radial section through one of the pistons of the moulding-series, and the devices for operating and controlling the same;

Figure 5, a central longitudinal section of one of the several two-part flasks required in moulding; and

Figures 6, 7, and 8, representations of three certain distinct parts of each one of the moulding-series detached.

Like letters of reference indicate the same parts when in the different figures.

The object of my invention is to facilitate and expedite the moulding of patterns in sand for castings; and

The nature of my invention consists in simultaneously charging the flask with sand, making the impression of the pattern therein, and withdrawing the pattern by a single stroke of a piston, or its equivalent.

My invention also consists in the construction and arrangement of certain mechanical devices, substantially as hereinafter described and specified, whereby the said piston, or its equivalent, is caused to charge the flask with the sand, make the impression of the pattern therein, and withdraw the said pattern at one operation or stroke of the said piston, or its equivalent.

Referring to the drawings,

A is the moulding-platform, supported by columns B-B, upon a substantial base, C.

D-D, the piston-heads, and D'-D' their stems or rods.

E-E, boxes or cases in the platform A, for receiving the piston-heads D, and the sand in which the patterns are to be moulded.

F-F, the patterns, detachably fixed on the piston-heads.

G-G, four horizontal shafts, each of which has one of its bearings in the support H, and has fixed on that end a disk, I, which has a wrist-pin, i, near its periphery, by which the said disk is connected with, and like a crank, operates its respective piston through the

media of a sliding block, J, and transverse slot K, in the broader part of the piston-rod D', whilst the opposite end of the said shaft G has its bearing in a stationary centre-post, L.

Each of these shafts, G, has, on its inner end, a loose bevel-pinion, M, and between the latter and the disk I, a sliding clutch, N, which receives a "fin," g, fixed on the said shaft, (see fig. 6,) and thereby gives rotary motion to the shaft when the said clutch N is slipped inward, into connection with the pinion M on the said shaft, by means of a hand-lever, P, which is connected with a spring, O, that embraces the clutch N, and a foot, O', which serves as a treadle, whereby the piston-rod D', on its descent, throws the clutch N out of connection with the pinion.

Each of the pinions M, gears with the upper side of a horizontal bevel-wheel, Q, which is loose on the centre-post L, and is rotated by a bevel-pinion, R, which gears with the under side of Q, and is fixed on a horizontal shaft, which is rotated by means of the vertical wheel R' on the same shaft, and the pinion S on the shaft of the balance-wheel T. (See fig. 2.)

Each piston-head, D, of the series, fits accurately in its respective case E, and has its lower edges d'-d", (see fig. 4,) made chisel-shaped, so as to clear the sand from the inside surface of the case as the head descends, the piston-rod D' being supported in a vertical position, centrally, under its head D, and so that it will slide, accurately, up and down in a hole in its stationary support d". (See figs. 3 and 4.)

When the piston is at its lowest position, the upper surface of its head D, forms the bottom of its respective case E, and the lower end of its rod D' bears on the treadle O', so as to draw the clutch N out of connection with the pinion M, the facing ends of the said clutch N and pinion M, having respective projections n' n' and m' m', (see figs. 4, 7, 8,) whereby they will interlock with each other when the clutch is pushed inward by means of the hand-lever P, and become separated again when the treadle O' is pressed downward by the piston-rod D'.

The position of the wrist-pin i, in the disk I, is such that when at its highest point, the upper surface of the piston-head D will be in the same plane with the upper surface of the moulding-platform A, and when at its lowest point, the lower end of the rod D' will draw the clutch out of connection with the pinion M, by pressing down the treadle O'.

The patterns F-F, with their moulding-plate, are detachably secured on the upper surfaces of the respective piston-heads, so that others can be substituted when required.

The flasks (see fig. 5) are each cast of metal, in two like halves U-U, so that when adjusted together in the usual manner, the flask will form a close case, with the exception of the necessary sprue-hole u' and vent-holes u"-u"; and so that the inner sides and ends will

slope inward, and then round off into the flat vented side, substantially as represented in the figure.

In the present instance the flask is represented as cast, with outside projections V-V, to support it on one end whilst the metal is being poured into the sprue u' in the other end.

The meeting-edges of the two parts of the flask, have also flanges, W-W, projecting horizontally outward around the same, whereby they can be readily secured to each other, and also to the platform A, directly over, and so as to entirely cover the mouths of the cases E, as shown in fig. 3. The relative capacity of each half U, of the flask, and of the case E, is such, that an evenly-filled case of the loose sand, when the piston-head is at its lowest position, will exactly fill the half flask U with the moulded or pressed sand, as represented in fig. 3.

The half flasks U are each detachably secured over the respective cases E, in the platform A, by means of two horizontally-moving racks e' e', operated on the outside of the case E by a pinion, e'', (see dotted lines fig. 3,) and a hand-crank, e'''.

The projecting ends of the racks e' e' have elbows extending back to a slot, a' a', in the platform, and carry clutch-blocks e⁴ e¹, which project up through the said slots, near each end of the flask U, in such a manner that by rotating the crank-handle a'', the said clutch-blocks e⁴ will be simultaneously caused to catch over the projecting edges of the flask, and hold it firmly down upon the platform A, or release the same, as occasion may require.

The two halves of the flask are each provided with lugs u'' u''' u'', and studs a'' a''' are fixed in the platform, around the cases E, whereby the said parts of the flasks are adjusted with facility and accuracy over the cases E.

Operation.

Supposing the piston-rods D' are all down upon the treadles O', and therefore the clutches N disengaged from the pinions M, if rotary motion be now given to the balance-wheel shaft, the horizontal bevel-wheel Q will be rotated around the centre-post L, and consequently each of the pinions M will be simultaneously rotated around its respective shaft G, and in this manner these parts are to be continually moving.

The attendant of each case E now proceeds (independently of each other) with the moulding-process.

A description of the mode of proceeding with one case will apply to all.

The tempered moulding-sand is filled loosely into the open case E, until even with the surface of the platform A, the half flask is then adjusted over the filled case, and secured by operating the hand-crank e'', so as to cause the clutch-blocks e'' e''' to clamp it firmly down upon the platform A, as shown in fig. 3. He then presses inward the hand-lever P, which, carrying inward the spring O, causes the clutch N to slide inward and interlock with the rotating pinion M, and consequently to be carried around with it, and thus give rotary motion to the shaft G and its disk I, and also an upward motion of the piston-head D, in the case E, until the upper surface of the said piston has reached the upper surface of the platform A, thus pressing the loose sand properly in the half flask U, above it, and at the same time making a perfect impression of the pattern F in the said sand, when the piston, with the pattern thereon, is caused to descend until the lower end of the piston-rod D', presses downward the treadle O' and thus withdraws the clutch N out of contact with the rotating pinion M, and stops any further movement of the said piston.

The attendant now detaches and removes the moulded flask, applies another, reversed, and proceeds as before, then joins the two moulded halves of the flask, and so continues until the time arrives for putting in the cores and casting, as heretofore.

It will be seen that the mode of moulding patterns in sand for castings, consisting in simultaneously charging the flasks with the sand, making the impression of the pattern therein, and withdrawing the pattern by a single stroke of a piston, or its equivalent, as described, will greatly facilitate and expedite the operation of moulding all small articles requiring only a two-part flask for the purpose, and especially such articles as turns, elbows, cocks, cross and branch-joints, required by plumbers, gas-fitters, and tube-manufacturers, and numerous other castings required in the arts.

Should the withdrawing of the pattern, by the return-stroke of the piston, fail to leave the impression in any manner imperfect, the attachment of the said pattern to the piston-head may be such, that when the piston retires, the pattern will remain in the sand, to be afterwards carefully removed by hand. This may be found desirable sometimes in very nice and delicate work.

This arrangement is illustrated in fig. 9 of drawings, where the pattern-bearing bed-piece, is provided with suitable pressure-pins z, which, acting against the insides of the half flask V, retain the said bed-plate with its patterns as the piston retires.

I do not claim attaching the pattern to the piston-head, and causing the impression of said pattern to be made in the sand by the forward motion of the said piston, for that is not new.

I do not claim, broadly, filling the flask with sand by machinery, for that is not new, and has been set forth in various inventions heretofore patented.

It will also be seen that the construction and arrangement of the different parts of the apparatus are comparatively simple, easily managed, and not liable to become deranged in use.

The structure and operation of my machine do not require that the sand-receiving cases E and the piston D should be arranged upon a circular bench. They may, if found more convenient, be arranged in line along the side of a moulding-room, and operated by an extended shaft.

Having thus fully described my invention,

What I claim as new, and desire to secure by Letters Patent, is confined to the following:

1. Moving at one and the same time both the sand and the pattern to the flask by the forward motion of the piston, when the said pattern is attached to the piston-head, so as to be withdrawn from the sand by the direct return-stroke of the said piston, all the said parts being constructed and arranged to operate substantially as and for the purposes specified and set forth.

2. I claim, in combination with the case E and platform A, arranged as described, the two racks e' e', the pinion e'', the crank e''', and the clutch-blocks e⁴ e¹, the said parts being arranged and combined to operate together, substantially as and for the purpose described.

3. I claim the spring-extension O of the treadle O', in combination with the clutch N and hand-lever P, constructed and arranged substantially as described, for the purpose of enabling the attendant to interlock the said clutch N with the pinion M, as occasion may require, as described.

4. I claim the construction and relative arrangement of the clutch N, spring O, treadle O', and piston-rod D', whereby the said piston-rod, as it reaches its lowest position, presses the said treadle downward, and thus causes the said spring to draw the said clutch out of connection with the rotating pinion M, substantially as described.
